UNITED STATES PATENT OFFICE.

JAMES TIMMS, OF COLUMBUS, OHIO, ASSIGNOR TO THE BUCKEYE MALLEABLE IRON AND COUPLER COMPANY, OF SAME PLACE.

DRAFT-RIGGING.

SPECIFICATION forming part of Letters Patent No. 669,713, dated March 12, 1901.

Application filed July 17, 1900. Serial No. 23,954. (No model.)

To all whom it may concern:

Be it known that I, JAMES TIMMS, a resident of Columbus, in the county of Franklin and State of Ohio, have invented certain new and useful Improvements in Draft-Rigging; and I do hereby declare the following to be a full, clear, and exact description of the invention, such as will enable others skilled in the art to which it appertains to make and use the same.

10 My invention relates to an improved draft-rigging for cars, and more particularly to a metal draft-rigging for freight-cars, one object of the invention being to provide a draft-rigging which will be constructed entirely of metal, the component parts of which can be easily and quickly assembled and any one of which can be replaced with but comparatively slight expense in case of breakage.

15 A further object is to provide a draft-rigging with improved means for supporting the coupling.

With these objects in view the invention consists in certain novel features of construction and combinations and arrangements of parts, as will be more fully hereinafter described, and pointed out in the claims.

In the accompanying drawings, Figure 1 is a plan view illustrating my improvements, the car-floor being removed. Fig. 2 is a side view, partly in section. Fig. 3 is a view in section on the line *x x* of Fig. 1. Fig. 4 is a view in section on the line *y y* of Fig. 1; and Figs. 5, 6, and 7 are detached views of details of construction.

20 A represents the body truss-bolster, mounted beneath the car and in which the contracted inner end 2 of my improved metal buffing-block or draft-block 1 is secured by bolts 3. The outer end of the buffing or draft-block 1 is made on each side with outwardly projecting enlargements 4, having a central vertical tongue or tenon 5 to fit into grooves or mortises 6 in the inner ends of parallel metallic draft-irons 7 to prevent lateral displacement of the latter. The draft-irons 7 are spaced a suitable distance apart to receive between them the coupling B and are made at their inner ends on their outer faces with bosses 8, having holes therein to align 25 with holes in bosses 9 on the draft-block 1 for the reception of bolts 10 to securely lock the

draft-irons and block together. The draft-irons 7 are also provided on their outside faces at their front end with perforated lugs 11 to receive the ends of truss-rods 12, which latter are passed over a truss-block 13 on the bolster A and through a transverse bar 14, held against brackets 15, secured to the timbers of the car, and nuts 16 are provided on the respective ends of the truss-rods to rigidly support the draft-rigging.

Bolts 17 and 18 pass through the floor of the car and block 1 and draft-irons 7, respectively, and four of the latter also secure to the bottom face of the draft-irons a recessed tie-plate 19.

The coupling B is mounted between the draft-irons 7 and has secured at its inner end by means of bolts 21 a vertically-disposed yoke 22, in which are mounted transverse followers 23, provided in their opposite faces with large central seats 24 for a large coiled spring 26, surrounding a small coiled spring 26^a, and smaller seats 25 are made at the four corners of the followers for smaller springs 27 to press one of said followers against the end of the coupling and the other against the vertical member of the yoke, and the ends of followers 23 are mounted to move in diametrically opposite pockets 28 in the draft-irons, the ends of said pockets forming abutments to limit the movement of the followers and contract the springs, and hence give to the coupling an elastic connection with the draft-irons to relieve any shock thereto. The outer ends of the draft-irons are made in their inner side faces with diametrically opposite pockets 29 to seat-springs 30, adapted to bear against opposite sides of the coupling to permit the same yielding lateral movement.

A transverse plate 3 is secured beneath the forward end of coupling B by four bolts 32, two of which pass through the main sill 32^a and the other two pass through the buffer-bases 32^b to support the coupling in proper position.

A transverse key 33 is passed through the coupling and aligned slots 34 in the draft-irons, and, if desired, draft-rod 35 may be connected at one end to the key 33 and passed rearward and connected at its other end to a similar key in the coupling at the other end of the

car to form a continuous draft-rigging. In order to get the benefit of the draft-springs at both ends of the car, a tail-pin is provided which is secured at the end of the coupling 5 and passes through the draft-springs and follower-plates. When this continuous rod connection is used, the yoke is not used, and when the yoke is used the draft-rods are dispensed with.

10. It will be seen that the coupling B is supported between two parallel draft-irons removably secured to the draft or buffering block, and that in case of breakage of either of said draft-irons the damaged part can be readily 15 removed and replaced by a new one without disconnecting the coupling or removing any other part of the draft-rigging.

Various slight changes might be made in the general form and arrangement of parts 20 without departing from my invention, and hence I would have it understood that I do not wish to be limited to the precise details shown, but consider myself at liberty to make such changes and alterations as fairly fall 25 within the spirit and scope of my invention.

Having fully described my invention, what I claim as new, and desire to secure by Letters Patent, is—

30. 1. In a draft-rigging for cars, the combination of a single metal draft or buffering block adapted to be secured to a car, parallel draft-irons adapted to support a coupling between them and means for removably securing the draft-irons to the end of said draft or buffering

block at respective sides of the longitudinal 35 axis thereof.

2. In a draft-rigging for cars, the combination of a metal draft or buffering block adapted to be secured to the bolster of a car and parallel draft-irons removably secured to the 40 draft or buffering block and having mortise-and-tenon connection therewith.

3. In a draft-rigging, the combination of a draft or buffering block adapted to be secured to the bolster of a car, parallel draft-irons having 45 mortise-and-tenon connection with said draft or buffering block, bosses on the adjacent ends of the block and irons, bolts passed through said bosses and securing said block and irons together and truss-rods connecting 50 the free ends of the draft-irons with the car.

4. In a draft-rigging, the combination of a single metal draft or buffering block secured to the car, parallel draft-irons having pockets in their inner faces, springs in said pockets 55 and means removably securing the draft-irons to the end of the draft or buffering block at respective sides of the longitudinal axis thereof, of a coupling disposed between said draft-irons and springs and a yielding connection 60 between the coupling and said draft-irons.

In testimony whereof I have signed this specification in the presence of two subscribing witnesses.

JAMES TIMMS.
